[57] CLAIM

The ornamental design for a drum, as shown and described.

DESCRIPTION

FIG. 1 is a front, top and left side perspective view of a drum showing my new design;

FIG. 2 is a rear, top and left side perspective view;

FIG. 3 is a top plan view;

FIG. 4 is a left side elevational view;

FIG. 5 is a front elevational view;

FIG. 6 is a right side elevational view;

FIG. 7 is a view like FIG. 1 of a modified form of a drum showing my new design, wherein the front is rectangular instead of square, the head oval instead of circular, and there is a band around the rear of the shell and a grip on the handle;

FIG. 8 is a view like FIG. 2 thereof;

FIG. 9 is a view like FIG. 3 thereof;

FIG. 10 is a view like FIG. 4 thereof;

FIG. 11 is a view like FIG. 5 thereof;

FIG. 12 is a view like FIG. 6 thereof; and

FIG. 13 is a rear elevational view thereof.
